CLAIM

The ornamental design for a printer panel, as shown and described.

DESCRIPTION

FIG. 1 is a front, top and right side perspective view of a printer panel showing our new design;

FIG. 2 is a rear, top and left side perspective thereof;

FIG. 3 is a front elevation thereof;

FIG. 4 is a right side elevation view thereof;

FIG. 5 is a rear elevation view thereof;

FIG. 6 is a left side elevation view thereof; and,

FIG. 7 is a top plan view thereof.

The bottom of the printer is not shown and is not claimed.

(Continued)

The features shown in broken lines depict environmental subject matter only and form no part of the claimed design.
